UNITED STATES PATENT OFFICE.

IDALIA J. STEWART, OF PORTLAND, OREGON.

WAIST AND SKIRT SUPPORTER AND FASTENER.

1,190,479.

Specification of Letters Patent.

Patented July 11, 1916.

Application filed April 27, 1915. Serial No. 24,261.

To all whom it may concern:

Be it known that I, IDALIA J. STEWART, a citizen of the United States, residing at Portland, in the county of Multnomah and 5 State of Oregon, have invented a new and useful Waist and Skirt Supporter and Fastener, of which the following is a specification.

The device forming the subject matter 10 of this application is a means for connecting a skirt removably with a waist, the construction being such that the weight of the skirt will not be carried into the waist.

Another object of the invention is to 15 provide a means whereby the fasteners on the waist and the skirt may be detached from the parts wherewith they are assembled, to facilitate a washing of the garment.

It is within the province of the disclosure 20 to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that changes in the precise embodiment of the 30 invention herein disclosed can be made within the scope of what is claimed, without departing from the spirit of the invention.

In the accompanying drawing:—Figure 1 is a rear elevation showing a garment constructed in accordance with the present invention; Fig. 2 is a front elevation of the waist, the skirt being removed; Fig. 3 is a fragmental vertical section taken through the band portions of the waist and skirt; 40 Fig. 4 is a fragmental elevation showing a portion of the skirt; Fig. 5 is a fragmental elevation looking into the interior of the skirt and toward the back thereof; Fig. 6 is an elevation showing a portion of the 45 waist band; Figs. 7 and 8 are perspective views depicting the fasteners employed in one form of the invention; Fig. 9 is an elevation looking at the exterior of the waist, at the back thereof; Fig. 10 is an elevation 50 looking into the interior of the skirt at the back thereof; Fig. 11 is an elevation showing a modified form of fastener; Fig.

12 is a section on the line 12—12 of Fig. 11; Fig. 13 is an elevation showing a modified form of fastener; Fig. 14 is a section on the 55 line 14—14 of Fig. 13.

In the accompanying drawings, the numeral 1 indicates a waist to the lower edge of which is secured a tubular band 2, the ends of the band 2 being open at the front 60 as shown at 3 in Fig. 2. The opening at the front of the waist is shown at 4. In the tubular band 2 are formed lateral apertures 5. Disposed adjacent the apertures 5 are fasteners 6 comprising upright slots 7 65 and a transverse eye 8. Through the tubular band 2 is inserted a flexible element in the form of a tape 9, the same being formed into loops 9^a extended through the lateral apertures 5 of the band 2 and engaged 70 through the openings or slits 7 in the fasteners 6. The tape 9 preferably is of sufficient length so that the free ends 22 thereof may be tied together at the front of the waist 1, as clearly shown in Fig. 2. 75

The skirt is shown at 23 and the skirt band is indicated at 10. Secured to the skirt band 10 and located upon opposite sides of the opening 14 at the back of the skirt 23 are tubular supplemental bands 11, the ends 80 12 of which are open. In the tubular supplemental bands 11 are formed apertures 15. Disposed adjacent each aperture 15 is a fastener 16 having upright slits 17 and equipped with a hook-shaped tongue 18 85 adapted to coöperate with the eye 8. Disposed within the tubular supplemental bands 11 and extended across the opening 14 at the back of the skirt 23 is a flexible element in the form of a tape 19, formed 90 into loops 19^a which protrude through the apertures 15 and are engaged in the slits 17. The ends 20 of the tape 19 are provided with snap fasteners 21 adapted to coöperate with snap fasteners 24 on the tape 9 and exposed through openings 25 in the band 2 of the waist 1. 95

In practical operation, the tongues 18 of the fasteners 16 which are assembled with the skirt 23 are engaged in the eyes 8 of the 100 fasteners 7 which are assembled with the waist 1. The snap fasteners 21 on the ends of the tape 19 which is carried by the skirt 23 are engaged with the fasteners 24 car-

ried by the tape 9 of the waist 1. The tape 9 is then tightened up, and its ends 22 are tied together at the front.

From the foregoing it will be obvious that the tapes 9 and 19 may be detached readily from the garments wherewith they are assembled, to permit a washing of such garments and for other purposes.

In Figs. 11 and 12, a modified form of fastener is shown. In the said figures, the tapes are denoted by the reference characters 30 and 31, the tape 30 being passed through openings 32 in a plate 33 having a headed stud 34 adapted to be engaged by 15 an eye 35 on a plate 36 having openings 37 through which the tape 31 is threaded.

In Figs. 13 and 14, of the drawings, one tape is denoted by the numeral 40 and the other tape appears at 41. By means of tubular rivets 42, an eye 43 is assembled with the tape 41 and by means of tubular rivets 44, a hook 45 is connected to the tape 40, the hook being adapted to engage the eye, as will be understood readily by those skilled in the art.

The only changes contemplated in Figs. 11 and 13 are in the suspension fasteners which replace the elements shown in Figs. 7 and 8, the invention remaining otherwise unchanged.

The devices shown in Figs. 7 and 8, 11 and 13 are separable fasteners of general application and adapted to be used on neck-

wear, brassières, horse blankets and under other circumstances which will suggest 35 themselves readily to the user.

Having thus described the invention, what is claimed is:—

1. In a device of the class described, co-operating members comprising a skirt and a waist; a flexible element circumscribing one of said co-operating members and having detachably connected ends; a second flexible element partially circumscribing the other of said co-operating members; means for detachably connecting the second specified flexible element adjacent its ends with the first specified flexible element; and detachably interengaged suspension members on the flexible elements. 50

2. In a device of the class described, a waist; a flexible element extended around the waist and having detachably connected ends; a skirt; a flexible element assembled with the skirt; snap fasteners connecting the ends of the last specified flexible element with the first specified flexible element; and detachably interengaged suspension members on the flexible elements. 55

In testimony that I claim the foregoing as my own, I have hereto affixed my signature in the presence of two witnesses.

IDALIA J. STEWART
